DESIGN FOR AN ENSEMBLE DRESS

Jack Kirschner, New York, N. Y.

Application April 15, 1935, Serial No. 56,375

Term of patent 3½ years

To all whom it may concern:

Be it known that I, Jack Kirschner, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

The rectangular structure at the front of the double pleated collar represents an inserted piece of lace.

The cross hatched lines at the front and back of the sleeves on the jacket represent Shirring.

The diagonal lines at the front of the waist of the dress represent darts, and the vertical lines commencing from the belt at the back of the dress represent inverted tucks.

I claim:

The ornamental design for an ensemble dress, substantially as shown and described.

JACK KIRSCHNER.
